UNITED STATES PATENT OFFICE.

WILLIAM B. TROWBRIDGE, OF BALDWINSVILLE, NEW YORK.

DESIGN FOR A TABLE-CHAIR.

50,767.

Specification for Design.

Patented May 8, 1917.

Application filed March 20, 1917. Serial No. 156,205. Term of patent 3½ years.

To all whom it may concern:

Be it known that I, WILLIAM B. TROWBRIDGE, a citizen of the United States, residing at Baldwinsville, in the county of Onondaga and State of New York, have invented a new, original, and ornamental Design for Table-Chairs, of which the following is a specification, reference being had to the accompanying drawings, forming a part thereof.

The figure is a perspective view of a table-chair showing my new design.

What I claim is:

The ornamental design for a table-chair as shown.

WILLIAM B. TROWBRIDGE.

Witnesses:

M. MURDOUGH,
J. F. WILLIAMS.
